SUCKER ROD SOCKET

Filed Aug. 19, 1927

2 Sheets-Sheet 2

UNITED STATES PATENT OFFICE.

ALBERT H. NEILSON, OF TULSA, OKLAHOMA.

SUCKER-ROD SOCKET.

Application filed August 19, 1927. Serial No. 214,099.

My invention relates to sucker rod sockets and more particularly to a device of that character for recovering broken or disconnected sucker rods from wells.

5 Sucker rods of the character employed for pumping oil wells are sectional, with each section provided at one end with a coupling box and at the other end with a pin adapted for threaded connection with co-operating 10 coupling members on other rod sections to form a string.

Because of heavy duty on the rods and occasionally due to conditions in a well, a rod will break or sections of it become disconnected at a coupling. When this occurs it is necessary to remove the upper part of the string and "fish" for and remove the part remaining in the well. If the rod has become disconnected at a coupling a tool 20 adaptable for receiving and grasping the pin on the upper end of the lost portion of the string must be employed. If the rod has broken, then a smaller tool for taking the rod is used. Attachment of the tool to 25 the box or rod is effected through expandable slips having tapered fittings in a housing barrel, so that they may open to receive the box or rod and close thereonto when the socket is lifted.

30 While such an arrangement is effective for finding and lifting the rod, there is a tendency of the slips to "freeze" or stick to their barrel when the load is heavy so that it becomes difficult to separate the tool 35 from the rod when the rod has been recovered.

It is the principal object of my invention to provide a socket of the character described which may be adapted for receiving either 40 a pin or rod when let into a well, which will securely hold the pin or rod during the lifting travel and which may be readily removed from the pin or rod when the rod is recovered.

45 In accomplishing this object, I have provided improved details of structure, the preferred forms of which are illustrated in the accompanying drawings, wherein:

Fig. 1 is a perspective view of part of a 50 well, illustrating a socket about to be applied to the pin of a lost section of sucker rod.

Fig. 2 is an enlarged longitudinal section of the socket, showing the parts as they appear while the socket is being lowered in a 55 well.

Fig. 3 is a similar view illustrating application of the socket to the rod pin.

Fig. 4 is a similar view, showing the parts as they appear while the rod is being raised.

Fig. 5 is a similar view illustrating expansion of the slips to release the rod.

Fig. 6 is a cross section on the line 6—6, Fig. 2, showing the parts as they appear while the socket is being lowered in a well.

Fig. 7 is a detail perspective view of the 65 coupling plug.

Fig. 8 is a detail perspective view of the slip cap and one of the slips.

Referring more in detail to the drawings:

1 designates a well hole, 2 casing lining the 70 hole and 3 tubing through which oil is pumped from the well by means of a pump (not shown) located in the well and operated by a sucker rod 4 in accordance with common practice.

75 The rod 4 is formed in sections, each equipped at its upper end with a pin 5 comprising an enlarged wrench head 6 and an upwardly extending threaded shank 7 adapted to be received in a threaded socket 80 in a box on the lower end of an adjacent rod section (not shown). The complete structure comprising the wrench head and threaded shank is usually referred to as the "pin" and such parts are intended when the term is used in the present description.

85 The socket, designated generally at 8, comprises a cylindrical barrel 9 of an outside diameter to permit its free passage through the tubing 3 and of a reducing inside diameter forming a downwardly restricted, tapered bore or throat 10 terminating in a flared mouth 11 for facilitating application of the socket to the loose end of a rod standing in a well.

90 The upper end of the barrel is internally threaded at 12 for attachment to a coupling plug 13, presently described, and is provided, near its upper end, with ports 14 for the relief of sand or other foreign matter 100 from the upper portions of the barrel.

95 The plug 13 has a flange 15 engaging the end of the barrel for limiting projection of the plug into the barrel and a reduced neck 16, and extending centrally through the plug is a screw-threaded channel 17.

100 Located within the tapered part of the barrel 9 is a set of slips 18, each tapered reversely to the barrel to wedge therein when moved outwardly under the conditions pres-

ently described and having upwardly directed annular teeth 19 on its inner surface at its outer end. Each of the slips is provided at its upper end with an inturned flange 20 having an upwardly directed lip 21 combined to form a reduced neck and an annular seat 22. The lower edges of the slips are beveled to form a receiving mouth like that at the lower end of the barrel.

23 designates a combination suspension and jack screw having a head 24 movable within the slip chamber, a neck 25 slideable in the collar 22 at the upper end of the slip seat and a shank 26 threaded through the channel 17 in the coupling plug 13. The end of the shank 26 projects beyond the plug 12 and attached to the projecting end of the shank, preferably by a pin 28, is a collar 29, bearing a wrench face to which a tool may be applied for turning the collar on the screw and in abutment with the end of the coupling plug to shift the screw in the coupling plug for adjusting or opening the slips. The end of the screw shank projects beyond the collar 29 for attachment to the box 30 (Fig. 1), on the end of a rod 30' whereby the socket is let into and removed from the well.

Slidably mounted on the screw shank 26 within the barrel 9 above the slips is a follower 31, adapted for seating on the lips 21 of the slips and comprising a depending rim flange 32 adapted for projection into the slip seat 22 and an upstanding collar 33 forming a spring seat 34. 35 designates an expansion spring which surrounds the screw shank with its lower end surrounding the follower collar and bearing against the seat 34 and its upper end bearing against the bottom of the coupling plug 13 to yieldingly retain the slips at the outer end of the barrel and in contracted relation.

Assuming the socket to be constructed and assembled as described and that it is to be employed for removing the part of a string of rods remaining in a well after an accidental uncoupling at a joint, the operation is as follows:

The upper part of the string of rod sections is recovered from the well and the lower end of the recovered rod observed to determine the nature of the break, here shown as a disconnection of a box and pin, as from stripping of the coupling threads. A socket containing a set of slips of a size to receive a pin is therefore attached to a rod section and let into the well, the spring 35 retaining the parts in the relation illustrated in Fig. 2. When the socket reaches the lost rod section the mouth of the socket centers the rod and the pin is received within the socket as the latter is lowered. When the slips move over the pin, they are forced back against the tension of the spring and open to receive the pin; the encompassing

movement continuing until the slips are spread back to contact with the barrel and the pin wedged between the slips. The socket is then lifted, the teeth on the slips gripping the pin and the slips being drawn down in the barrel by weight of the rod. As the slips move downwardly in the barrel, the reverse taper of the barrel and slips forces the slips in against the pin to grip the pin firmly within the slips, the upwardly directed teeth on the slips biting into the pin to insure the holding relation. The letting in rod is then raised, lifting the lost socket rod.

When the upper end of the lost rod section has been raised above the well head, a spider is applied to the rod and the socket recovered by driving the barrel down along the slips to spread the slips and relieve the rod.

Should the slips "freeze" or stick to the barrel so that they cannot be separated by ordinary methods, a wrench may be applied to the collar 29 and the screw drawn up to elevate the slips and permit them to spread (Fig. 5) and relieve the pin.

Should separation of the rod be due to a break between the ends of a rod section, a set of slips of sufficiently less interior diameter to grip the rod is used instead of the set of pin slips and the operation of finding, gripping and elevating the rod performed as above described.

While restriction of the lower end of the barrel is sufficient to prevent insertion and removal or loss of the slips through that end of the barrel, ready access to the barrel chamber for insertion and removal of the slips may be had from the upper end upon removal of the coupling plug.

What I claim and desire to secure by Letters Patent is:

1. A socket of the character described including a barrel having a tapered inner wall at one end and a plug at the opposite end having a threaded channel, slips in said barrel tapered reversely to the barrel and having inturned end flanges forming a channel, a screw threaded through the barrel plug, having a shank slideable in the slip channel and a head engageable with the slip flanges, a follower on the shank engageable with the slips, a spring interposed between the barrel plug and follower to project the slips, and a nut fixed on the screw for retracting the slips.

2. A socket of the character described including a barrel having a tapered inner wall at one end and a plug at the opposite end having a threaded channel, slips in said barrel tapered reversely to the barrel having inturned end flanges and outturned lips, forming an inner channel and outer seat at the end of the slip unit, a follower having an outturned rim flange projected into said

- seat, a screw threaded through the plug channel having a shank slideable in the follower and slip channel and a head engageable with the slip flanges, a spring surrounding the screw end engaging the barrel plug and follower to extend the slips, and a wrench receiving member fixed to the screw to retract the slips against the tension of said spring.
- 5 3. A socket of the character described including a barrel having ports for the relief of foreign matter, and having a tapered inner wall at one end and a plug at the opposite end having a threaded channel, slips in 10 said barrel tapered reversely to the barrel having inturned end flanges and outturned lips, forming an inner channel and outer seat at the end of the slip unit, a follower having an outturned rim flange projected into said seat, a screw threaded through the 20 plug channel having a shank slideable in the follower and slip channel and a head engageable with the slip flanges, a spring surrounding the screw and engaging the barrel plug and follower to extend the slips, and a wrench receiving member fixed to the screw to retract the slips against the tension of said spring.
- 15

In testimony whereof I affix my signature.

ALBERT H. NEILSON.
